UNITED STATES PATENT OFFICE.

ROBERT L. COONEY, OF ATLANTA, GEORGIA.

DRY-PIPE WATER-SERVICE FIRE-EXTINGUISHER SYSTEM.

1,075,019.

Specification of Letters Patent.

Patented Oct. 7, 1913.

Application filed June 15, 1910. Serial No. 567,049.

To all whom it may concern:

Be it known that I, ROBERT L. COONEY, a citizen of the United States, residing at Atlanta, in the county of Fulton and State 5 of Georgia, have invented new and useful Improvements in Dry-Pipe Water-Service Fire-Extinguisher Systems, of which the following is a specification.

This invention relates to improvements 10 in dry-pipe water service fire extinguisher systems. The advantages of this type of fire protection installation are well known to those skilled in the art and therefore will not be detailed in this specification. It is 15 pertinent, however, to state that those systems which have met with any commercial consideration and which will be generally referred to in succeeding paragraphs, have been of the pressure controlled type. In 20 fact, the development of the art has been almost exclusively along this line, since systems of mechanical control are not commercially acceptable by reason of being expensive, cumbersome, and slow in action. The 25 principle heretofore employed in dry-pipe systems, as they are termed, has involved the opposition of a restraining elastic fluid pressure to the pressure of the water in the city main through the intermediary of the 30 dry-pipe valve, the latter being usually of a differential type, and having its faces so proportioned that a given pressure of elastic fluid will efficiently oppose a given pressure of the water in the city mains. In 35 these systems the elastic fluid pressure is put into the distributing pipe and its leaders or branches; and normally holds the dry-pipe valve in its closed position. When, however, a sprinkler head or distributing 40 valve is opened, the fluid pressure exhausts from the distributing system and the force of the water, being thus unopposed, causes the dry-pipe valve to open, the water in the service main being thus admitted to the dis- 45 tributing system. In a few instances the restraining elastic fluid pressure has not been opposed to the city water pressure but has been opposed to a weight or some equivalent arrangement which is operatively as- 50 sociated with or related to the dry-pipe valve to produce the opening of the latter but which has its operation normally re- strained by the action of the elastic fluid pressure. In one or two of the last-men- 55 tioned variations of the general type, the restraining pressure is used to initially con-

trol an operating pressure through the intermediary of some mechanical device.

One objection to the type of system generally described above may be traced from the fact that the principle employed proposes the opposition of a restraining force which may vary from a maximum to zero to an operating force which can never fall to zero and which, to all intents and purposes, is fixed. By reason of this fact, if, on account of leakage of the elastic fluid pressure, the restraining force should be reduced below the absolute degree essential for normally preventing the opening of the dry-pipe valve by the operating force, whether the latter be derived from the service pressure, from a weight, or from a maintained or originated elastic fluid pressure, said operating force will be unbalanced or permitted or caused to become active, and hence, will produce the opening of the dry-pipe valve, and the conversion of what was originally intended to be a dry-pipe system into a wet-pipe system. It will be apparent that this anomalous condition renders the valve organization wholly inutile and superfluous. The leakage of the restraining pressure, above referred to, is only one of the factors which will produce the result stated. In some instances, by reason of a defect or inherent peculiarity of the mechanical organization, the undesirable result will follow from other conditions, unnecessary to detail. Another objection to the type of system referred to may be traced from the fact that, out of a necessary abundance of precaution, the restraining pressure is put into the distributing pipes at a degree more or less in excess of the degree necessary to prevent the action of the valve and it follows from this that a substantial reduction of pressure has to occur throughout the whole distributing system before the valve can come into action. As a consequence, there is a greater or less degree of delay prior to the mechanical action of the arrangement and which, by increasing the period of time necessary for the stream to reach the fire, seriously interferes with or minimizes the efficiency of the system. This period of delay is of course augmented to a greater or less degree by the character and mode of operation of the mechanical agents employed.

The foregoing preliminary discussion leads to a statement of the main objects of the

present invention and these are first, to provide a system of the type stated wherein there is absolutely no liability of the ultimate conversion of a dry-pipe system into a wet-pipe system; second, to provide a system wherein the preliminary period of delay is reduced to a minimum and is governed almost wholly by the extent of the distributing system, being negligibly affected by the nature and mode of operation of the mechanical agents employed; and third, to provide a dry-pipe valve organization of the simplest and most inexpensive character. The manner in which these objects are carried out will appear from a consideration of the example disclosed in the accompanying drawing, wherein—

Figure 1 is a diagram of the system; and Fig. 2 is a vertical longitudinal section of the dry-pipe valve organization.

Similar characters of reference designate corresponding parts throughout the several views.

In the diagram, A designates the service or supply pipe, B is the general designation of the dry-pipe valve organization, C designates the distributing pipe, D designates a leader from the distributing pipe, and E designates a sprinkler head associated with the leader.

The dry-pipe valve organization includes a closed casing, as 1, to the interior of which access may be had through a hand hole, normally covered by a closure plate, as 2. This casing is operatively related to the pipes A and C, the pipe A being connected directly to the casing and the pipe C being connected directly to a siphon casting, as 2^a, which in turn is connected directly to the casing at one side thereof, and is, in effect, a component part or lateral continuation thereof. The casting 2^a embodies an up-flow channel 3 leading from the casing, a down-flow channel 4 leading to the distributing pipe C, and a web 5 intervening between the channels.

In contemplation of the particular organization and mode of operation herein disclosed by way of example, the casing is partially filled with water up to a line X, a portion of the body of water of course occupying the channel 3. This body of water which, in the example under consideration, is the equivalent of a mechanical element and is to be so considered, provides for an air space, as 6, in the upper portion of the casing and for an air space, as 7, in the upper portion of the siphon casting, and of course serves to separate these air spaces. The air space 7 is obviously in direct communication with the distributing system.

The communication of the service or supply pipe A and the casing is normally interrupted by a disk or plate valve 10. In the present example, this valve is carried by the

lower one of a pair of toggle links 11, being for a purpose which will hereinafter appear, pivoted thereto. The upper link 11 is pivoted at the end of an adjusting stem 12, the threaded and swiveled shank of which passes through a web 13, and carries a hand wheel 14.

The links 11 are initially set slightly off their line of dead center and this relation is normally maintained by a latch lever 15 pivoted between its ends to a bracket 16, and which has one end formed to engage or hook over a lug 17 on the upper link 11 and its other end free. It will be apparent, from the description thus far given, that the closed relation of the valve 10 is maintained through an agency which exercises this, its normal function, by reason of an inherent quality, and not by reason of the application of a restraining pressure as in the known constructions of the type referred to. Consequently the force (pneumatic pressure) which initiates the opening of the valve 10 is derived from a source extraneous to the city water pressure notwithstanding that such water pressure is, in the embodiment disclosed, instrumental in effecting the actual opening of said valve 10. In this, as well as in other respects to presently appear, the invention involves, so far as I am aware, a new principle of organization and operation and a new technological effect.

The opening of the valve 10 which, in the present example, is effected by the pressure of the water in the pipe A, is provided for, by raising the engaging end of the lever 15 to clear the lug 17, and this action is consequent to the descent of a float 18 which is sustained in a normal position by the body of water aforesaid, which descends consequent to the lowering of the level of said body of water, and which, in its descent, engages the free end of the lever 15 and trips the latter, with the result stated. The float 18 surrounds and moves with relation to an axially disposed guide stem, as 18^a, and is provided with a flange or bead, as 18^b, for engagement with the free end of the lever 15.

The invention contemplates the use of an elastic fluid impulse or pulsation to provide for the opening of the valve and in the embodiment under discussion this pulsation of course acts upon the body of water aforesaid, and in the preferred mode of operation the impulse or pulsation is applied to that portion of the body of water which is confined in the casing 1.

In the preferred mode of operation a charging pressure is employed and this pressure is put both into the distributing system and into the casing, that division of pressure in the distributing system being, for the sake of convenience and clearness, termed the restraining or dominant pressure, and that

division of pressure in the casing being, for the same reason, termed the operating or servient pressure. These restraining and operating pressures are, of course, separated by the body of water aforesaid and at the same time are effective in determining or maintaining the level of the latter.

In order that the water level may remain at the normal position determined upon, it is essential that the restraining and operating pressures should always be equal. The simplest contemplation of the result stated involves a normal equalizing of the pressures and this is accomplished by connecting the air spaces of the casing 1 and the siphon casting 2^a by a by-pass pipe, as 19, which may be of capillary diameter or, and preferably may, as shown, be provided with a diaphragm 20 which has a "pin-hole" aperture. It will be apparent that, with this arrangement, if the degree of either of the pressures is slightly and gradually reduced, as by reason of leakage, the degree of the other pressure will be correspondingly reduced, owing to the communication of the pressures through the pin hole of the diaphragm. While the diameter of the "pin-hole" aperture aforesaid is amply sufficient in providing for the equalizing of the pressures in the manner and under the circumstances set forth, it is too small to pass any material portion of the operating pressure when the restraining pressure is suddenly and materially reduced, as at the time of a fire by the opening of a sprinkler head, distributing valve, or equivalent device. Consequently, when the pressures are unbalanced in the manner set forth, by the opening of a valve, in the event of a fire, the restraining or servient pressure does not escape, to any material degree, through the apertured diaphragm 20, but becomes active in the casing 1 and projects the body of water toward the distributing system, thus lowering the water level and providing for the descent of the float 18. The latter thereupon trips the lever 15 in the manner explained, the toggle links are thereby released, and the water in the pipe A forces the valve 10 from its seat and flows past said valve and into the distributing system.

The foregoing operations take place in an almost incredibly short period of time, and this quickness of action which amounts practically to instantaneousness, is due to the correlated facts, first, of the suddenness and initial force of the operating impulse or pulsation, and second, of the several characteristics of the mechanical instruments whose action is in response to the pulsation. In the embodiment under consideration, these characteristics are the lightness of the body of water, the simplicity of the valve locking means, and the siphon effect of the column of

water passing through the downflow channel 4, this last being augmentative of the action of the impulse or pulsation. These three characteristics combine to produce a sensitiveness of mechanical action, which in conjunction with the suddenness and force of the impulse, renders the operating effect of the latter of the most efficient character. This sensitiveness of mechanical action, in addition to its material contribution to the efficiency of operation of the system, makes it possible to produce the operation with an impulse of exceedingly light character, and of course, in the preferred mode of operation, the charging pressure may be maintained at a very low degree. The importance of this fact will be appreciated when it is considered that the lighter the pressure, the more easy it is to maintain, that provision for a light maintained pressure is a positive requirement of the art, and that the important object of a great number of prior arrangements is to provide for a light restraining pressure.

The present invention provides for the use of pressure at a degree, both as concerns the function of operation and the function of restraint, which is several times less than the lightest degree of pressure heretofore possible and the degree of pressure necessary to the operation of the present system may, out of an abundance of precaution, be increased several times and still be lower than the lowest degree of pressure heretofore possible. When a charging pressure is used, it may be introduced into the system at any convenient point, and from any convenient source. It is preferred, however, to introduce this pressure into the air space 6, through an opening 21 in the wall of the casing and the air may be supplied through a reducing valve and a carboy. The reducing valve and the carboy are not shown; the mention of the elements in passing is thought to be sufficient, since they are well known in this and other arts for generally similar purposes.

Out of an abundance of precaution it is preferred to provide means of simple and inexpensive character and whereby the action of the apparatus will not be affected, either by the leakage of water past the valve 10 and into the casing, or from the casing, although with a reasonable degree of care in manufacture and proper factory inspection, either of the contingencies noted will be very remote.

To overcome the effect of leakage past the valve 10 and into the casing, means is provided for automatically maintaining the water level determined upon and such means includes a drain pipe 22 which communicates with the casing below the water line and which is normally closed by a valve 23, carried at one end of a bell crank lever 24. The

latter is pivoted at the junction of its arms to a lug or bracket, as 25, and has a free arm which projects above the float 18. The lever 24 is so hung that the valve 23 normally closes the inlet end of the pipe 22. It will be apparent that in the event of such leakage into the casing as would temporarily raise the water level, the float 18 will ascend and in such movement will engage the free arm of the lever 24, thereby rocking the latter and unseating the valve 23. Thereupon the excess of water is drained through the pipe 22 and this draining is, of course, continued until the water level is approximately at the determined height. At such time the lever 24 will have resumed its normal position and the valve 23 will close against the end of the pipe 22 and interrupt further drainage through said pipe. It will be noted that by having the inlet end of the pipe 22 below the normal water line the degree of pressure of the air maintained in the space 6 is not affected.

To overcome the effect of leakage of water from the casing means is provided for automatically maintaining the water level determined upon and such means includes a pipe, as 26, which extends between the pipe A and the bottom of the casing and which has its discharge end normally closed by a valve, as 27. The latter is placed at the end of a stem 28, slideable axially through apertured lugs 29 and having an attached weight 30 which effects the normal seating of the valve 27.

It will be apparent that in the event of leakage or evaporation of the water in the casing, the water level will be lowered and the float 18 will descend. The unseating of the valve 27 is consequent to the descent of the float and is produced by a pivoted finger, as 31, which is engaged and moved by the float and which in turn engages the weight 30 and raises the stem 28 and therewith the valve 27. Water is thus admitted into the casing from the pipe 26 until the level has been restored to the height determined at which time the float 18 will have resumed its normal position and the valve 27 will have seated by gravity, thus interrupting the further admission of water through the pipe 26. The finger 31 serves another function which is incidental to the operation of the system, namely, to prevent the ascending movement of the float after the latter has moved sufficiently to provide for the opening of the valve 10 and in this function the finger acts as a pawl and engages a flange 32 at the lower end of the float. This provision is made, since, if the float were allowed to ascend after its operation and consequent to the filling of the casing 1 with water from the pipe A, it would cause the opening of the valve 23 in the manner explained and hence some of the water in-

tended for service demands would be uselessly diverted and the pressure at the open sprinkler head or distributing valve would be, to that extent, reduced.

The invention is believed to be of considerable novelty within its particular field and for this reason no specific description herein contained is intended to place any limitation upon the scope of the succeeding claims, which does not inhere in the language thereof.

Having fully described my invention, I claim:

1. A dry-pipe fire extinguisher system including a water service pipe, a distributing pipe and a closed casing interposed between the water service pipe and the distributing pipe and communicating with said pipes, the distributing pipe and the casing serving to confine air under pressure, means for maintaining the pressures of the air in the distributing pipe and in the casing at equal degrees, a valve arranged in the casing and which, in a normal position, closes the water service pipe, the casing being partially filled with a body of liquid which separates the air in the casing from the air in the distributing pipe and provides for the expansion of the air in the casing, when the air in the distributing pipe is suddenly exhausted, means for latching the valve in its closed position, and a float supported by the body of liquid and operable consequent to the shifting of the latter when the air in the casing expands to disengage the valve latching means.

2. A dry-pipe fire extinguisher system including a water service pipe, a distributing pipe and a closed casing interposed between the water service pipe and the distributing pipe and communicating with said pipes, the distributing pipe and the casing serving to confine air under pressure, means for maintaining the pressures of the air in the distributing pipe and in the casing at equal degrees, a valve arranged in the casing and which, in a normal position, closes the water service pipe, a pair of toggle links, one of which is pivoted to the valve and the other of which is pivoted in the casing, the toggle links being normally set slightly off a dead center and maintaining the closed position of the valve, a latch lever which engages the toggle links and maintains the normal relation thereof, a body of liquid which separates the air in the casing from the air in the distributing pipe and provides for the expansion of the air in the casing when the air in the distributing pipe is suddenly exhausted, and a float supported by the body of liquid and operable consequent to the shifting of the latter when the air in the casing expands to engage the latch lever and cause the latter to release the toggle links.

3. A dry-pipe fire extinguisher system including a distributing pipe, a water service pipe, a casing interposed between the pipes and in communication therewith, a valve in the casing and normally closing the water service pipe, the casing being partially filled with a body of liquid which is shiftable by a pneumatic impulse whereby its level in the casing is lowered, and means operable consequent to the shifting of the body of liquid to provide for the opening of the valve.

4. A dry-pipe fire extinguisher system including a distributing pipe, a water service pipe, a casing in communication with the water service pipe, a siphon casting in communication with the casing and the distributing pipe, a valve in the casing and normally closing the water service pipe, the casing and the siphon casting being partially filled with a body of liquid which is shiftable by a pneumatic impulse whereby its level in the casing is lowered, and means operable consequent to the shifting of the body of liquid to provide for the opening of the valve.

5. A dry-pipe fire extinguisher system including a distributing pipe, a water service pipe, a casing interposed between the distributing pipe and the water service pipe and in communication with said pipes, a valve in the casing and normally closing the water service pipe, the casing being partially filled with a body of liquid whereby air spaces are afforded on the distributing pipe side and the casing side of said body, a by-pass pipe connecting the air spaces and having an air passageway of "pin-hole" diameter, the body of liquid being shiftable by a pneumatic impulse whereby its level in the casing may be lowered and means set in operation consequent to the lowering of the level of the body of liquid to provide for the opening of the valve.

6. A dry-pipe fire extinguisher system including a distributing pipe, a water service pipe, a casing interposed between the distributing pipe and the water service pipe and in communication with said pipes, a valve in the casing and normally closing the water service pipe, the casing being partially filled with a body of liquid whereby air spaces are afforded on the distributing pipe side and the casing side of said body, a by-pass pipe connecting the air spaces and having an air passageway of "pin-hole" diameter, means for latching the valve in a closed position, the body of liquid being shiftable by a pneumatic impulse whereby its level in the casing may be lowered and a float operable consequent to the lowering of the level of the body of liquid to disengage the valve latching means.

7. A dry-pipe fire extinguisher system including a distributing pipe, a water service pipe, a casing interposed between the dis-

tributing pipe and the water service pipe and partially filled with a body of liquid maintained in stable equilibrium and shiftable by a pneumatic impulse developed within the casing, the action of which is initiated by a sudden reduction of pressure in the distributing pipe, a valve in the casing and normally closing the water service pipe, and means operable consequent to the shifting of the body of liquid to provide for the opening of the valve.

8. A dry-pipe fire extinguisher system including a distributing pipe, a water service pipe, a casing interposed between the distributing pipe and the water service pipe and partially filled with a body of liquid shiftable by a pneumatic impulse, a valve in the casing and normally closing the water service pipe, and means for latching the valve in a closed position and operable consequent to the shifting of the body of liquid to provide for the opening of the valve.

9. A dry-pipe fire extinguisher system including a distributing pipe, a water service pipe, a casing interposed between the distributing pipe and the water service pipe and partially filled with a body of liquid shiftable by a pneumatic impulse, a valve in the casing and normally closing the water service pipe, a float shiftable with the body of liquid, and means caused to operate by the shifting of the float to provide for the opening of the valve.

10. A dry-pipe fire extinguisher system including a distributing pipe, a water service pipe, a casing interposed between the distributing pipe and the water service pipe and partially filled with a body of liquid which normally has a determined level and is shiftable by a pneumatic impulse, a valve in the casing and normally closing the water service pipe, means operable consequent to the shifting of the body of liquid to provide for the opening of the valve, and automatically operable drain valve means for relieving the casing of any excess of liquid which may leak past the valve.

11. A dry-pipe fire extinguisher system including a distributing pipe, a water service pipe, a casing interposed between the distributing pipe and the water service pipe and partially filled with a body of liquid which normally has a determined level and is shiftable by a pneumatic impulse, a valve in the casing and normally closing the water service pipe, means operable consequent to the shifting of the body of liquid to provide for the opening of the valve, a pipe connecting the service pipe and the casing and a valve normally closing said last-named pipe and operable automatically to open and admit liquid to the casing in the event of leakage or evaporation of the liquid normally contained therein.

12. A dry-pipe fire extinguisher system

including a distributing pipe, a water service pipe, a casing interposed between the distributing pipe and the water service pipe and partially filled with a body of liquid 5 shiftable by a pneumatic impulse, a valve in the casing and normally closing the water service pipe, a float shiftable with the body of liquid, means caused to operate by the shifting of the float to provide for the opening 10 of the valve, and a drain valve automatically operable by the float in the event of the raising of the liquid level by reason of leakage past said first-named valve to relieve the casing of excess liquid and to restore the normal liquid level.

13. A dry-pipe fire extinguisher system including a distributing pipe, a water service pipe, a casing interposed between the distributing pipe and the water service pipe 20 and partially filled with a body of liquid shiftable by a pneumatic impulse, a valve in the casing and normally closing the water service pipe, a float shiftable with the body of liquid, means caused to operate by the shifting of the float to provide for the opening 25 of the valve, a pipe connecting the service pipe and the casing and a valve normally closing said last-named pipe and operable automatically in the event of the loss of liquid from the casing and consequent to the descent of the float to move to open position and thereby admit sufficient water to the casing to restore the normal water level.

14. A dry-pipe fire extinguisher system including a distributing pipe, a water service pipe, a casing interposed between the distributing pipe and the water service pipe and partially filled with a body of liquid 30 shiftable by a pneumatic impulse, a valve in the casing and normally closing the water service pipe, a float shiftable with the body of liquid, means caused to operate by the shifting of the float to provide for the opening 35 of the valve, a drain valve automatically operable by the float in the event of the raising of the liquid level, by reason of leakage past said first-named valve to relieve the casing of excess liquid and to restore the normal liquid level, a pipe connecting the service pipe and the casing, a valve normally closing said last-named pipe, and a pivoted finger for opening the last-named valve, the finger being operable by 40 the float consequent to the descent of the latter in the event of the loss of liquid from the casing and having operation also to engage the float and maintain the latter in a lowered position subsequent to the opening 45 of said first-named valve.

15. A dry-pipe fire extinguisher system including a distributing pipe, a casing communicating therewith and partially filled with a body of liquid, in stable equilibrium 55 but shiftable by a pneumatic impulse de-

veloped within the casing, the action of which is initiated by a sudden reduction of pressure in the distributing pipe, a water service pipe communicating with the casing, a valve normally closing the water service pipe, means associated with the valve to maintain the closed relation of the latter and having a wholly mechanical action in this function, and means operable consequent to the shifting of the body of liquid to cause the first-named means to provide for the opening of the valve.

16. A dry pipe fire extinguisher system including a distributing pipe, a water service pipe, a casing interposed between the distributing pipe and the water service pipe, a valve normally closing the water service pipe, and means in stable equilibrium in the casing, but operable by a pneumatic impulse to provide for the opening of the valve, the means including a yieldable element which has air spaces at opposite sides thereof in the casing and in the distributing pipe respectively, and which provides for the development of the impulse within the casing as an immediate consequence of a reduction of pressure in the distributing pipe.

17. A dry pipe fire extinguisher system, including a distributing pipe, a water service pipe, a casing interposed between the distributing pipe and the water service pipe, a valve normally closing the water service pipe, means for latching the valve in its closed position, and means in stable equilibrium but operable by a pneumatic impulse for disengaging the valve latching means, the means including a yieldable element which has air spaces at opposite sides thereof in the casing and in the distributing pipe respectively, and which provides for the development of the impulse in the casing as an immediate consequence of a reduction of pressure in the distributing pipe.

18. A dry pipe fire extinguisher system, including a distributing pipe which serves to confine air under pressure, a casing communicating with the distributing pipe and also serving to confine air under pressure, a restricted communication between the distributing pipe and the casing to normally maintain the air pressures at equal degrees, a water service pipe, communicating with the casing, a valve normally closing the water service pipe, and means in stable equilibrium in the casing and operable by the expansion of air in the casing when the air in the distributing pipe is suddenly exhausted, to provide for the opening of the valve.

19. A dry pipe fire extinguisher system, including a distributing pipe, a casing in communication therewith, a water service pipe communicating with the casing, a plate valve in the casing and normally closing

the water service pipe, a pair of toggle links, one of which is pivoted in the casing and the other of which is pivoted to the plate valve, a latch lever engaging the toggle links and causing the latter to hold the plate valve in its closed position, and means for causing the latch lever to release the toggle links and including a yieldable element which is arranged in stable equilibrium and is operatively movable by a pneumatic impulse, developed within the casing consequent to a reduction of pressure in the distributing pipe.

20. A dry pipe fire extinguisher system, including a distributing pipe, a casing communicating therewith and partially filled with a body of liquid which has air spaces at opposite sides thereof in the casing and in the distributing pipe respectively, a water service pipe communicating with the casing, a valve arranged in the casing to normally close the service pipe, the air pressure in the casing being normally balanced by the air pressure in the distributing pipe whereby it expands when the pressure in the distributing pipe is suddenly and materially reduced, and means set in operation conse-

quent to such expansion to provide for the opening of the valve.

21. A dry pipe fire extinguisher system, including a distributing pipe, a water service pipe, and a closed casing in communication with the distributing pipe and the water service pipe and partially filled with a body of liquid, the distributing pipe and the tank each serving to confine an elastic fluid under pressure, means for maintaining the fluids at normally equal pressures, a valve held normally to close the water service pipe, the elastic fluid in the tank expanding when the elastic fluid in the distributing pipe is suddenly exhausted, and means set in operation consequent to the expansion of the pressure in the casing to provide for the opening of the valve, the tank inclosing the valve and the means.

In testimony whereof I have hereunto set my hand in presence of two subscribing witnesses.
